PICKER CHECK FOR LOOMS

Carl P. Bergstrom, Millbury, Mass., assignor to
Crompton & Knowles Loom Works, Worcester,
Mass., a corporation of Massachusetts

Application November 26, 1948, Serial No. 62,213

9 Claims. (Cl. 139—168)

1

This invention relates to improvements in picker checks for looms and it is the general object of the invention to provide a check which arrests motion of a shuttle and is then locked momentarily so that it is incapable of causing reverse motion of the shuttle in a direction out of the shuttle box.

Fly shuttle looms are customarily made with some form of check to arrest momentum of the shuttle as it enters the shuttle box. Some of these checks combine lateral friction exerted by a binder against the shuttle with a means to exert end force on the shuttle, the latter means frequently taking the form of a flexible strap or the like which extends across the path of the picker to check the latter as the shuttle approaches the end of its travel. In the past it has been customary to mount these straps on spring actuated drums which after checking the shuttle exert a force tending to move the shuttle out of the shuttle box.

It is an important object of the present invention to lock the picker check in the position to which it is moved by the shuttle to prevent it from moving the shuttle from its properly boxed position. At some time in the cycle of the loom subsequent to picking the check is released, permitting it to move to correct position for the next checking operation.

In multi-shuttle looms the shuttle boxes usually shift between front and top center positions, the shuttle entering its box as the lay moves forwardly and the box then shifting while the lay is in the forward part of its motion. Picking ordinarily occurs when the lay is on top center or approximately half way between back and front center positions and moving rearwardly. It is a further object of the invention to hold the aforesaid picker check locked throughout the time the shuttle boxes are shifting and then effect unlocking subsequent to completion of box shift. This result may be accomplished as set forth herein by causing unlocking of the check as the lay approaches its rearmost position.

With these and other objects in view which will appear as the description proceeds, the invention resides in the combination and arrangement of parts hereinafter described and set forth.

In the accompanying drawings, wherein a convenient embodiment of the invention is set forth, Fig. 1 is a front elevation of part of a loom having the invention applied thereto,

Fig. 2 is an enlarged plan view looking in the direction of the arrow 2, Fig. 1,

2

Fig. 3 is a front elevation looking in the direction of arrow 3, Fig. 2,

Fig. 4 is a cross section on line 4—4, Fig. 3, and

5 Fig. 5 is an enlarged view of the lower left hand part of Fig. 2 showing the relation between the locking pawl and the stationary cam which releases the pawl as the lay approaches its rear position.

10 Referring particularly to Fig. 1, the loom frame 10 supports a bottom shaft 11 having secured thereto a picking arm 12 for cooperation with a picking cam 13 on a picker shaft 14. The latter is operatively connected by power arm 15, sweep stick 16 and lug strap 17 to a picker stick 18 pivoted at its lower end as at 19 to a rocker iron 20 on a rocker shaft 21.

The lay 25 is provided with a gang GL of shifting shuttle boxes, four shuttle boxes or cells designated from top to bottom at 26—29, respectively. These shuttle boxes are mounted on a box lifter rod 30 which is raised by a chain 31 and is lowered by gravity and also by a spring 32. This chain is operated by a well-known mechanism not

25 set forth herein and acts when required to shift the shuttle boxes starting when the lay is on bottom center and continuing through front center until the lay reaches top center. When the lay is at top center the picker stick 18 operates

30 to pick the shuttle which is aligned with the shuttle race 33. On the next pick of the loom the shuttle is picked from the opposite side of the lay and enters the shuttle box in picking position, which, as shown in Fig. 1, is the top cell 26.

35 Each shuttle box is provided with a binder 34 which exerts lateral frictional force on a shuttle entering the shuttle box. This frictional force is not always sufficient to stop the shuttle completely, and it is customary to utilize some additional 40 means for bringing the shuttle finally to rest.

The loom will ordinarily include in its construction some mechanism for controlling the sequence of shifting of the gang GL, and also rising and falling of the harness frame not shown.

45 This mechanism may include a chain 35 supported by a chain run 36 which is held in stationary position on the loom. The invention is not limited in its use to such types of pattern and shuttle box and harness actuating mechanism as suggested at the upper left hand part of Fig. 1, and the run 36 is set forth herein merely to provide a stationary part of the loom behind the lay and located adjacent to the outer or left end of the shuttle boxes as indicated in Fig. 1.

55 Shuttle S engages and is propelled by a picker

stick actuated picker 37 slidable on a picker spindle 38 mounted on the lay behind the gang GL. As the shuttle enters the active shuttle box it pushes the picker outwardly or to the left as viewed in Fig. 2. The picker has a picking head 39 for engagement with the tip 40 of the shuttle. The shuttle boxes shift between inner and outer shuttle box guides 41 and 42 on the lay shown respectively at the right and left of Fig. 1. The picker and the spindle, however, will remain at the same level and will not shift with the shuttle boxes, and the picker will always remain registered with the active shuttle box.

The mechanism thus far described is of common construction and operates as already described. While Fig. 1 shows a gang of shuttle boxes the invention is not necessarily limited to use with multiple shuttles, but can if desired be used with a single shuttle box. The timing of picking will be substantially the same whether a single shuttle box or a shifting gang of shuttle boxes is employed.

As already suggested the picker has in the past been acted upon by some form of supplementary check additional to the shuttle binders to bring the shuttle to final rest in correct position for shifting of the gang GL. One type of these checks includes a strap and coil spring which holds the strap taut across the path of the picker as the latter is moved by the shuttle, but such a check acts on the shuttle to move it out of the shuttle box, or in a right hand direction as viewed in Fig. 2. It is the general purpose of the present invention to provide a control which will prevent the check from moving the shuttle out of the shuttle box.

In carrying the invention into effect a support plate 50 is secured as at 51 to the outer box guide 42 and has an upward extension 52 provided with a horizontal slot 53. Extending through the slot is a stud 54 having a flange 55 and a bearing end 56 to the right of the flange, Fig. 4. Between the flange 55 and the upward extension 52 of the support plate there is located a flat sheet metal plate or pawl carrier 57. When the nut 58 is tightened it draws the flange 55 against the pawl carrier and extension 52 to hold these two parts clamped tightly together in fixed position. By loosening the nut 58 the stud and plate 57 can be adjusted horizontally.

Rotatably mounted on the bearing part 56 of the stud is a drum or rotary member 60 around a portion of which is wrapped a flexible strap or member 61 the upper end of which is attached to the drum by a screw 62. This flexible member may be leather or similar material and has its lower end secured as at 63 to some part of the lay, such as the lay end 64 which extends to the left from the lay 25; see Fig. 1. A coil spring 65 surrounds the hub 66 of the drum and has the left end thereof as viewed in Fig. 4 held in fixed position relatively to the stud, this result being accomplished by bending the end of the spring and extending it into a recess 67 in the flange. The other end 68 of the spring bears against a part 69 of the drum. The effect of the spring is to tend to turn the drum in a counter-clockwise direction as viewed in Fig. 3, or in a direction to straighten the strap 61. The latter is positioned for engagement with the head 39 of the picker as shown for instance in Figs. 2 and 3.

A part of the periphery of the drum 60 is provided with ratchet teeth 70 which cooperate with a pawl 71 pivoted on a stud 72 fixed as by riveting to the plate 57. This pawl is acted upon by

a torsion spring 73 which surrounds an enlarged part 74 of the stud 72. The forward end 75 of spring 73 enters a part of the plate 57 and is held in stationary position with respect to the lay, while the rear end 77 of spring 73 enters the hub 78 of the pawl. The effect of spring 73 is to turn the holding tooth 79 of the pawl toward the ratchet teeth 70. The pawl has an upwardly extending stud 80 on which is rotatably mounted a roll 81 which not only rotates on the stud 80, but also swings about the axis of the stud 72 as the pawl moves angularly.

The previously described pattern chain guide or run 36 has secured thereto a cam member 85 held in horizontally adjusted position by bolt 86 on the run 36. The part 85 is provided with a forwardly extending cam 87 having a face 88 which is inclined rearwardly and outwardly with respect to the shuttle box. This face 88 is placed for engagement with the roll 81 as the lay approaches its back center position.

In operation, a shuttle entering the shuttle box aligned with the lay will force picker head 39 against the strap 61, deflecting the same from the position *a* to *b*, Fig. 3. This effects an angular motion of the drum 60 in a clockwise direction as viewed in Fig. 3 to a given angular position in which it is held by engagement of the ratchet teeth 70 with the pawl 79. The latter is therefore able to prevent retrograde, or counter-clockwise movement of the drum as viewed in Fig. 3; and the strap will not tend to move the shuttle inwardly, as in previous checks.

The shuttle is boxed while the lay is in the forward part of its motion with the roll 81 spaced forwardly from the cam 87, as shown in Fig. 5. As the lay moves rearwardly from its forward position the shuttle is picked with the roll 81 still spaced forwardly from surface 88. Further continued backward movement of the lay causes roll 81 to engage face 88 to effect counter-clockwise rocking of the pawl from the full to the dotted line position shown in Fig. 3. The drum is thus released and the spring 65 turns the drum back to its normal position to straighten the strap, as at *a* in Fig. 3. This will effect movement of the picker toward the center of the loom should the picker be in contact with the strap, but this movement of the picker occurs after the shuttle has left the shuttle box. In any event the picker upon the next arrival of the shuttle in the shuttle box will have its outward movement resisted by a force derived from spring 65 and exerted through the strap 61.

From the foregoing it will be seen that the invention sets forth simple means for checking the final motion of the shuttle in such manner that no forces are exerted tending to move the boxed shuttle toward the center of the loom. The check remains locked by reason of the pawl and ratchet mechanism until after the shuttle is picked and is then able to return to its normal position by engagement of the roll 81 with the cam 88 as the lay approaches back center. Furthermore, the check is maintained locked throughout the shifting period of the gang GL. Adjustment of the check in a horizontal direction is afforded by slot 53 in the support 50, and the plate 57, which moves horizontally with the stud 58 during such adjustment, carries the pawl with it so that the distance between the axes of the pawl and drum remains fixed for all horizontal adjustments of the check.

Having thus described the invention it will be seen that changes and modifications of the fore-

going specific disclosure may be made without departing from the spirit and scope of the invention.

What is claimed as new is:

1. In picker checking mechanism for a loom having a picker moved by a shuttle when the latter enters a shuttle box on the lay, a flexible strap having one end thereof fixed with respect to the lay, rotary means on the lay operatively connected to the other end of the strap, resilient means acting on the rotary means normally causing the latter to maintain the strap taut across the path of the picker, the latter when moved by the shuttle bending the strap and causing angular movement of the rotary means from the normal position thereof to a given position, pawl and ratchet means operatively interposed between the lay and rotary member effective to hold the latter in said given angular position, and means operating due to motion of the lay causing the pawl and ratchet means to release the rotary means.

2. The picker checking mechanism for a loom having a picker moved by a shuttle when the latter enters a shuttle box on the lay, a flexible strap having one end thereof fixed with respect to the lay, rotary means on the lay operatively connected to the other end of the strap, resilient means acting on the rotary means normally causing the latter to maintain the strap taut across the path of the picker, the latter when moved by the shuttle bending the strap and causing angular movement of the rotary means from the normal position thereof to a given position, ratchet teeth secured to and turning with the rotary means, a pawl pivotally mounted with respect to the lay effective by engagement with the ratchet teeth to hold the rotary means in said given position, and means acting due to movement of the lay to move the pawl out of engagement with said ratchet wheel.

3. In picker checking mechanism for a loom having a picker moved by a shuttle when the latter enters a shuttle box on the lay, a checking member moved from the normal position thereof to an abnormal position thereof by the picker when the latter is moved by the shuttle, resilient means tending to move the checking member from the abnormal to the normal position thereof, holding means acting upon movement of the checking member to abnormal position to hold the member in abnormal position against the action of said resilient means, and means moving the holding means out of holding relation relatively to the checking member after the shuttle has been picked from the shuttle box.

4. In picker checking mechanism for a loom having a shuttle which enters a shuttle box on the lay and moves a picker at a given point in the cycle of the loom and is picked from the shuttle box at a later point in the loom cycle, a checking member tending to move the picker against the shuttle in a direction to move the shuttle out of the shuttle box, the shuttle when entering the shuttle box causing the picker to move the checking member oppositely to said direction to an abnormal position at said given point in the loom cycle, holding means acting between said given and later points in the loom cycle controlling the checking member and preventing the same from moving the picker, and releasing means acting subsequent to said later point in the loom cycle causing the holding means to relinquish control of the holding means.

5. In picker checking mechanism for a loom

having a shuttle which enters a shuttle box on the lay and moves a picker at a given point in the cycle of the loom and is picked from the shuttle box at a later point in the loom cycle, a flexible strap one end of which is fixed with respect to the lay, a rotary member mounted on the lay for angular movement relatively thereto, the other end of the strap being connected to said rotary member, resilient means operatively connected to said rotary member tending to keep the strap taut and tending to move the picker in the direction in which the shuttle moves when picked out of the box, the picker when moved by the shuttle at said given point bending the strap and causing angular movement of the rotary member to a given angular position thereof, ratchet teeth fixed relatively to the rotary member, a pawl pivotally mounted relatively to the lay engaging the ratchet teeth between said given and later points in the loom cycle to hold the rotary member in said given angular position thereof, and means effective subsequent to said later point in the loom cycle to move said pawl out of engagement with said ratchet teeth.

6. In picker checking mechanism for a loom having a lay provided with a picker which is moved outwardly when a shuttle enters a shuttle box on the lay, a flexible member extending across the path of said picker and having one end thereof secured to the lay, a drum rotatably mounted on the lay having the other end of said flexible member attached thereto, a spring normally tending to turn said drum in a direction to keep said flexible member taut, ratchet teeth moving with said drum, a pawl pivotally mounted with respect to the lay effective to engage said ratchet teeth and hold the drum against movement by said spring after said picker by engagement with said flexible member has caused angular movement of said drum, and means including a part stationary on the loom effective to move said pawl away from said ratchet teeth as the lay approaches the back center position thereof.

7. In picker checking mechanism for a loom having a picker moved by a shuttle when the latter enters a shuttle box on the lay, a flexible member having one end thereof fixed with respect to the lay and extending across the path of the picker, a drum rotatable on the lay operatively connected to the other end of the flexible member, resilient means acting on the drum normally causing the latter to maintain the flexible member taut, the picker when moved by the shuttle bending the strap and causing said drum to turn from the normal position thereof to a given position, ratchet teeth integral with said drum, a pawl pivotally mounted with respect to the lay effective by engagement with said ratchet teeth to hold said drum in said given angular position, a cam fixed with respect to the loom, and means cooperating with the cam and dependent upon rearward movement of the lay to move said pawl out of engagement with said ratchet teeth.

8. In picker checking mechanism for a loom having a picker moved along a path by a shuttle when the latter enters a shuttle box on the lay, a flexible strap having one end thereof fixed with respect to the lay, a drum rotatably mounted on the lay connected to the other end of the strap, resilient means acting on the drum normally causing the latter to maintain the strap taut across the path along which the picker is

moved by the shuttle, the picker when moved along said path bending the strap and causing angular movement of the drum from the normal position thereof to a given position, ratchet teeth turning with the drum, a pawl 5 pivotally mounted with respect to the lay effective by engagement with the ratchet teeth to hold the drum in said given angular position, a roll rotatable on the pawl, and a stationary cam for engagement with the roll, said roll and 10 cam cooperating due to backward movement of the lay and at a time subsequent to picking of the shuttle from the shuttle box to move said pawl out of holding engagement with respect to said ratchet teeth.

9. In picker checking mechanism for a loom having a picker moved by a shuttle when the latter enters a shuttle box on the lay, a flexible strap having one end thereof fixed with respect to the lay, a stud fixed to the lay in adjusted position relatively thereto in the direction of travel of the shuttle in the shuttle box, a plate operatively related to the stud and moving therewith when the stud is adjusted, a drum 20 rotatable on said stud and having the other end 25

of the strap secured thereto, resilient means tending normally to move the drum in a direction to maintain said strap taut across the path of the picker, the latter when moved by the shuttle bending the strap and causing angular movement of the drum to a given position, a pawl pivotally mounted on said plate, ratchet teeth moving with the drum engaged by the pawl to maintain the drum in said given angular position, and means dependent upon rearward movement of the lay and operating subsequent to picking of the shuttle from the shuttle box effective to move said pawl out of engagement with said ratchet teeth.
